UNITED STATES PATENT OFFICE.

JOHN R. COX, GEORGE H. WRIGHT, AND WILLIAM H. REYNOLDS, OF
GALVESTON, TEXAS.

STEAM-SEPARATING TRAP.

SPECIFICATION forming part of Letters Patent No. 655,611, dated August 7, 1900.

Application filed April 4, 1898. Renewed June 18, 1900. Serial No. 20,765. (No model.)

To all whom it may concern:

Be it known that we, JOHN R. COX, GEORGE H. WRIGHT, and WILLIAM H. REYNOLDS, citizens of the United States, residing at Galveston, 5 ton, in the county of Galveston and State of Texas, have invented a new and useful Steam-Separating Trap, of which the following is a specification.

This invention relates to an improved steam-separating trap or steam-eliminator for securing a supply of dry steam to an engine or other machinery to which it is desired to admit steam comparatively free from moisture and in as dry a condition as possible.

15 The present invention removes the surplus humidity from the steam, collects the water of condensation, and automatically discharges the accumulated water when the same reaches a predetermined level.

20 For a full understanding of the merits and advantages of the invention reference is to be had to the accompanying drawings and the following description.

The improvement is susceptible of various 25 changes in the form, proportion, and the minor details of construction without departing from the principle or sacrificing any of the advantages thereof, and to a full disclosure of the invention an adaptation thereof is shown 30 in the accompanying drawings, in which—

Figure 1 is a view in elevation of an automatic steam-separating trap constructed in accordance with this invention. Fig. 2 is a vertical section thereof. Fig. 3 is a plan section on the line X X of Fig. 1. Fig. 4 is a detail section showing the relation of the parts when the trap is exhausting.

40 Corresponding and like parts are referred to in the following description and indicated 40 in the several views of the drawings by the same reference characters.

The casing containing the vital parts is composed of an upper part 1 and a lower part 2, secured together in any convenient way, 45 preferably by having their opposing ends outwardly flanged and receiving bolts or machine-screws.

The upper portion of the casing is provided at its sides with offstanding collars 3, the one 50 constituting an inlet and the other an outlet

and each adapted to have the intercepted ends of a line of steam-pipe connected thereto. A baffle-plate 4 is located centrally of the casing and in the upper portion thereof and lies in a plane at right angles to a plane 55 passing centrally through the collars 3, so that the steam entering the inlet impacts against the baffle-plate and is spread there-over, thereby causing the moisture contained therein to be condensed and separated there- 60 from, the dry steam passing over the upper end of the baffle-plate and out through the outlet. In order to present a maximum amount of condensing-surface, the baffle-plate is fluted or corrugated. The lower end of the 65 baffle-plate is formed with a lateral flange 5, which limits the downward spread of the steam and prevents it passing beneath the baffle-plate, which would be objectionable, inasmuch as it would be liable to carry off a certain per- 70 centage of the water of condensation. This flange 5 inclines outwardly and downwardly and terminates a short distance from the adjacent wall of the casing, thereby providing a narrow passage for the escape of the water 75 of condensation received upon the flange 5 from the baffle-plate. Notched lugs 6 are formed with the sides of the casing and are located at different levels and receive the edge portions of the baffle-plate, which latter 80 is slipped into position from the open end of the casing when the cap 7 is removed.

The lower portion 2 of the casing, which forms the water-chamber of the device, receives a float 8, adapted to receive and contain water of condensation and to rise and fall upon the change of level of the water contained in the casing. As shown, the float is a bucket, which receives the water of condensation as the same accumulates. A discharge-pipe 9, leading to a convenient point of discharge, communicates with the lower portion of the casing, so as to siphon off the water when the same reaches a given level. This discharge-pipe passes through the casing at a distance from its lower end and communicates with a suction-pipe 10 within the casing and terminating a short distance from the bottom thereof. This pipe 10 extends within the bucket-float nearly or quite to the 100

bottom thereof, whereby very little water is left in the bucket when the discharge-pipe is through draining off the accumulated water prior to interrupting the communication 5 thereof with the interior of the trap. A fitting 11 is located about at the juncture of the pipe 9 with the casing, and this fitting contains a valve 12 and a piston 13, the latter operating in the outer branch of the fitting 10 and being in line with the valve 12 and the latter seating against the inner end of the branch of the fitting opposite and in line with the branch containing the piston 13. The area of the valve 12, against which the steam 15 exerts the pressure, is less than the area of the piston 13. Hence the difference in pressure is in favor of the piston, the superior pressure serving to hold the valve seated and the discharge-pipe closed.

20 A steam-pipe 14 connects the outer end of the fitting 11 with the upper part of the lower portion of the casing 2, and its receiving end is bent vertically within the casing, as shown at 15, and is adapted to be closed by a valve 25 16, which is controlled in its movements by the float 8 and the change of level of the water. A lever 17 is pivotally connected with an extension of the vertical end portion 15 of the steam-pipe 14 and passes transversely 30 through an opening of the valve 16. The inner or opposite end of the lever 17 has pivotal connection with the stem 18 of the float, whereby the movement of the float causes a corresponding movement of the valve 16. A 35 drain-pipe 19 has connection with the lower end of the casing and is supplied with a valve 20, which can be opened to admit of the water in the lower portion of the casing being drawn off and the sediment blown out.

40 When the device is interposed in a line of steam-pipe and the steam is passing therethrough, the excess of moisture is removed therefrom by means of a baffle-plate in the manner set forth. When the water of condensation in the lower portion of the casing or trap reaches a given level, the valve 16 is closed, thereby shutting off the supply of steam to the pipe 14 and permitting the valve to open by reason of the pressure thereon.

45 The water is forced out through the pipe 10 into the discharge-pipe 9 and carried off thereby to the point of discharge. The float being relieved of the weight of the water is buoyed upward and unseats the valve 16, 50 thereby permitting the steam to again pass through the pipe 14 and operate against the piston 13, whereby the valve 12 is forced upon its seat, thereby closing the communication between the discharge-pipe and the trap.

55 60 This opening and closing of the valve is automatic and takes place without any attention on the part of the operator.

It will be understood that while the trap is in use the lower portion of the casing thereof 65 is designed to hold sufficient water to normally float the bucket-float 8 when the lat-

ter is empty in a plane which unseats the controlling-valve 16, and thereby permits the steam under full pressure to pass through the pipe 14 and operate against the piston 11, thereby closing the valve 12 upon its seat and cutting off communication through the discharge-pipe 9. As the water of condensation accumulates in the bucket 8 such bucket necessarily becomes heavier and sinks within the water in the bottom of the casing until the valve 16 reaches its seat and cuts off the steam from the pipe 14, whereupon the pressure of steam is exerted against the accumulated water in the bucket with sufficient force to open the valve 12 and discharge the water through the pipe 9. The discharge of the accumulated water from the bucket 8 is quite rapid, and when the bucket is empty the same necessarily becomes sufficiently light to again float to a normal position and unseat the controlling-valve 16.

Having thus described the invention, what is claimed as new, and desired to be secured by Letters Patent, is—

1. A steam-trap, comprising a casing having a steam inlet and outlet and provided at the bottom with a water collecting and discharging chamber, a baffle-plate interposed between said inlet and outlet, a buoyant containing-float in the lower portion of the casing adapted to have a rise-and-fall movement and receive the water of condensation from the baffle-plate, said water of condensation also falling into the said chamber, a siphon discharge-pipe having one member thereof arranged within the float, a valve fitted to the siphon discharge-pipe, a steam-pipe connecting the upper portion of the collecting and discharge chamber with a part of the siphon 95 discharge-pipe exterior of the trap, said steam-pipe having a valve located within the collecting and discharge chamber and also provided with a chamber, a piston in the latter for controlling the valve in the discharge-pipe, and a connection between the float and the valve of the steam-pipe, whereby the valve of the discharge-pipe may be closed by the pressure of steam within the trap-casing.

2. A steam-separating trap comprising a casing having a steam inlet and outlet and provided at the bottom with a water collecting and discharge chamber, a bucket-float adapted to be buoyed by water of condensation within the water collecting and discharging chamber to have a rising-and-falling movement and also to receive and contain water of condensation, a siphon discharge-pipe having one member arranged within the casing and extending into the bucket-float, a valve in said siphon discharge-pipe, a steam-pipe having one portion located within the casing and provided with a valve and also with a chamber, said chamber being in communication with the valve of the discharge-pipe, a piston 110 in the said chamber for controlling the valve in the discharge-pipe, a connection between 115

the valve in the portion of the steam-pipe within the casing and the bucket-float, and means within the trap-casing above the float and the water collecting and discharging 5 chamber for separating purposes and directing the water of condensation downwardly into the float and said chamber.

In testimony that we claim the foregoing as

our own we have hereto affixed our signatures in the presence of two witnesses.
